UNITED STATES PATENT OFFICE.

HANS ANDERSEN, OF NYMORE, MINNESOTA.

LOG-SKIDDING GRAPPLE.

1,353,503.

Specification of Letters Patent. Patented Sept. 21, 1920.

Application filed June 9, 1919. Serial No. 302,789.

To all whom it may concern:

Be it known that I, HANS ANDERSEN, a citizen of the United States, residing at Nymore, in the county of Beltrami and State of Minnesota, have invented certain new and useful Improvements in Log-Skidding Grapples; and I do hereby declare the following to be a full, clear, and exact description of the invention, such as will enable others skilled in the art to which it appertains to make and use the same.

My invention has for its object to provide a log skidding grapple; and, to this end, it consists of the novel devices and combinations of devices hereinafter described and defined in the claims.

In the accompanying drawings, which illustrate the invention, like characters indicate like parts throughout the several views.

Referring to the drawings:—

Figure 1 is a plan view of the improved grapple in position to engage a log, some parts being broken away and sectioned;

Fig. 2 is a view partly in side elevation and partly in section of the parts shown in Fig. 1;

Fig. 3 is a fragmentary detail view, partly in plan and partly in section, taken on the line 3—3 of Fig. 2;

Fig. 4 is a fragmentary view, partly in elevation and partly in section, taken on the line 4—4 of Fig. 1;

Fig. 5 is a perspective view of the grapple head and a portion of the pulling link; and

Fig. 6 is a detail view, partly in elevation and partly in section, taken on the line 6—6 of Fig. 1.

The numeral 7 indicates a head that is bifurcated to afford a pair of upper and lower prongs 8, which, in turn, are bifurcated to afford pairs of hinge lugs 9. The head 7 is also provided with a square shank 10, which projects in an opposite direction from the prongs 8, and extending through its inner end portion, is a horizontal slot 11.

A pair of crossed and reversely curved grapple levers 12 extends between the prongs 8 and is pivotally connected thereto by a bolt 13. On the free ends of the long arms of the levers 12, are inwardly projecting barbs 14, and secured in the free ends of the short arms of said levers are links 15. These links 15 have interlocking engagement with a pulling link 16 having formed

therewith a sleeve 17 mounted on the shank 10. The sleeve 17 is square in cross section and closely fits the shank 10 on which it is free to slide endwise, but is held against turning movement thereon. A pair of notches 18 is formed in the sleeve 17 for registration with the slot 11, when said sleeve is moved toward the head 7. Of course, it is understood that a cable or chain, not shown, will be attached to the link 16 for dragging the log to which the grapple is secured over the ground.

To lock the long arms of the grapple levers 12 against opening movement, when closed onto a log Y, with their barbs 14 pressed therein, there is provided a latch comprising a segmental channel member 19 and a co-operating segmental bar member 20. The latch member 19 is rigidly secured to the intermediate portion of the short arm of one of the grapple levers 12 with its free end portion extending through the slot 11 and has ratchet teeth 21 on the bottom of the channel. The latch bar 20 is pivoted to the short arm of the other grapple lever 12, 70 loosely lies in the channel of the latch member 19, and is provided with ratchet teeth 22 adapted to interlock with the ratchet teeth 21. The ratchet teeth 21 and 22 are arranged to hold the short arms of the grapple levers 12 against spreading movement, and hence, a like movement of the long arms of said levers, but will freely slide over each other to permit the long arms of said levers to close. The notches 18 in the sleeve 17 afford clearance for the latch members 19 and 20, as shown in Fig. 1. A spring 23, secured to the same grapple lever 12 to which the latch member 20 is secured, bears against the latch bar 20 and yieldingly holds its ratchet teeth 22 interlocked with the ratchet teeth 21.

To positively hold the latch bar 20 with its ratchet teeth 22 interlocked with the ratchet teeth 21, there is provided a lock in the form of two short rods 24 and 25 connected by a turn-buckle 26. The outer end of the rod 24 is pivotally connected to the intermediate portion of the latch bar 20 and the other end of the rod 25 is bent to form a hook 27, which is interlocked with a slot 28 in a lug 29 on the short arm of the same grapple lever 12 with said latch bar. When the lock rods 24 and 25 are extended by the turn-buckle 26, to prevent separation of the

ratchet teeth 21 and 22, the hook 27 on the rod 25 bears against the outer end of the slot 28 as a base of resistance.

A pair of skid bars 30 have on one of their ends hinge lugs 31, which extend between the hinge lugs 9 on the head 7, and are pivotally connected thereto by hinge bolts 32 arranged to permit opening and closing movements of said skid bars, at right angles to like movements of the grapple levers 12. These skid bars are of substantially the same length and curve as the long arms of the grapple levers 12 and extend therebetween. On the inner faces of the other or free ends 15 of the skid bars 30 are holding lugs or bosses 33 arranged to engage a log Y, at diametrically opposite points, and thereby hold said skid bars against circumferential movement thereon. A multiplicity of longitudinally 20 extended ribs 34 are formed on the outer faces of the skid bars 30 and hold said skid bars from slipping edgewise, when in engagement with the ground Z.

The long arms of the grapple levers 12 25 are intermediately connected by a toggle lever 35, and the skid bars 30 are likewise connected by a toggle lever 36. A square link 37 affords the single intermediate joint between the members of the toggle levers 30 35 and 36. By a straightening movement of the toggle levers 35 and 36, the grapple levers 12 and skid bars 30 are simultaneously spread and by a buckling movement of said toggle levers, the grapple levers and skid bars are simultaneously closed.

A constant pull on the link 16 will, in itself, hold the grapple levers 12 closed onto the log with the barbs 14 pressed therein. In case the pull on the link 16 should be 40 come slack; for instance, when going down grade, the base of resistance for the locks 24, 25 and 26 might yield, by a slight spreading movement of the grapple levers 12, and thereby permit the latch bar 20 to move sufficiently to allow its ratchet teeth 22 to separate from the ratchet teeth 21, were it not for the spring 23.

When the improved log-skidding grapple is applied to a log, the grapple levers 12 extend substantially in a horizontal plane and the skid bars 30 extend in substantially a vertical plane, with the front end of the log resting on the lower skid bar, as shown in Fig. 2. This lower skid bar 30 acts as a 55 curved runner for the front end of a log and prevents the same from digging into the ground, ice or snow. The long arms of the grapple levers 12 and the skid bars 30 also act as a guard to guide the log past obstructions.

What I claim is:—

1. A log skidding device comprising a rigid head, a pair of coöperating grapple levers intermediately pivoted to said head, and a relatively wide skid bar pivoted at

its forward end to the head for vertical swinging movement in respect to the grapple levers.

2. A log skidding device comprising a rigid head, a pair of coöperating grapple levers intermediately pivoted to said head, and a pair of relatively wide skid bars pivoted at their forward ends to the head for vertical swinging movement in respect to the grapple levers. 75

3. A log skidding device comprising a rigid head, a pair of coöperating grapple levers intermediately pivoted to said head, a relatively wide skid bar pivoted at its forward end to the head for swinging movement transversely of the movement of said levers, a toggle lever connecting the grapple levers, and a connection between the skid bar and joint of the toggle lever, whereby the grapple levers and skid bar are simultaneously opened and closed. 80

4. A log skidding device comprising a pair of coöperating grapple levers, a pair of skid bars pivoted for movement transversely of the movement of the grapple levers, and two toggle levers, the one connecting the grapple levers and the other the skid bars, said two toggle levers being connected at their intermediate joints, whereby the grapple levers and skid bars are simultaneously opened and closed. 90

5. A log skidding device comprising a head, a pair of coöperating grapple levers intermediately pivoted to said head, a pair of skid bars pivoted to the head for movement transversely of the movement of the grapple levers, a pulling link having a sleeve slidably mounted on the head, and coupling links between the grapple levers and pulling link. 10

6. A log skidding device comprising a head, a pair of coöperating grapple levers intermediately pivoted to said head, a pair of skid bars pivoted to the head for movement transversely of the movement of the grapple levers, a pulling link having a sleeve slidably mounted on the head, coupling links between the grapple levers and pulling link, and connections for simultaneously opening and closing the grapple lever and skid bars. 11

7. A log skidding device comprising a bifurcated head, a pair of coöperating grapple levers intermediately pivoted to and between the prongs of said head, a pair of skid bars pivoted to the prongs of said head for movement transversely of the movement of the grapple levers, pulling connections between the grapple levers, and connections for simultaneously opening and closing the grapple levers and skid bars. 1

8. A log skidding device comprising a head, a pair of coöperating grapple levers intermediately pivoted to said head, pulling connections between said levers, and a latch 1

comprising two ratchet tooth - equipped members which, when interlocked, hold the long arms of the grapple levers against opening movement, one of said members being rigidly secured to one of the grapple levers and the other thereof being pivoted to the other of said grapple levers.

9. A log skidding device comprising a head, a pair of coöperating grapple levers intermediately pivoted to said head, pulling connections between said levers, a latch comprising two ratchet tooth-equipped members which, when interlocked, hold the long arms of the grapple levers against opening movement, one of said members being rigidly secured to one of the grapple levers and the other thereof being pivoted to the other of said grapple levers, and a spring under strain to hold the movable latch member interlocked with the fixed member thereof.
10. A log skidding device comprising a

bifurcated head, a pair of coöperating grapple levers intermediately pivoted to and between the prongs of said head, pulling connections between said levers, and a latch comprising a channel member rigidly secured to one of the grapple levers and extending through a slot in said head, a ratchet bar pivoted to the other grapple lever and extending into the channel latch member, said channel latch member having on its bottom ratchet teeth with which the teeth of the ratchet bar interlock to hold the grapple levers against opening movement.

In testimony whereof I affix my signature in presence of two witnesses.

HANS ANDERSEN.
